UNITED STATES PATENT OFFICE.

ANNA MADELINE WENZEL, OF BROOKLYN, NEW YORK.

GAUGE AND COOPERATING CUTTER.

Application filed May 27, 1927, Serial No. 194,716. Renewed July 1, 1929.

The present invention relates to gauges and co-operating cutters for application to a sewing machine, or other suitable piece of mechanism, and has for an object the more rapid and perfect control of the material to be cut.

It is also an object of my invention to provide a gauge and co-operating cutter for quick and convenient application to a sewing machine, and particularly to that class of sewing machines adapted to the hat industry.

With these and other objects in view, which will become apparent as the description proceeds, my invention consists of the novel parts and combinations of parts, all as hereinafter will be more fully described and particularly pointed out in the claims.

Referring to the accompanying drawings forming a part of this specification in which like numerals designate like parts in all the views.

Figure 1 is a side view of a small sewing machine equipped with my gauge and co-operating cutter.

Figure 2 is an enlarged view of my gauge dis-assembled.

Figure 3 is an end view of this sewing machine equipped with my gauge and co-operating cutter.

Figure 4 is a plan view of the feed mechanism of the sewing machine which is slotted to allow space for the cutter.

Figure 5 is the cutter support, cutter, and small auxiliary gauge, and

Figure 6 is one of my cutter supports, cutter, and auxiliary gauge dis-assembled.

In the drawings 10 is my gauge bracket adapted for attachment to the casting of the 40 bed-plate of the sewing machine 11 by means of the screw 12 and the dowel pin 13. The boss member 14 is drilled through vertically to provide a hinged bearing for the member 15 which swings about the large dowel pin 16 and the said member 15 is further equipped with a stationary dowel pin 17 adapted to enter a hole in the boss member 14 and to hold the member 15 firmly in closed position against the base member of 50 the sewing machine, except when the member is lifted, freeing the dowel pin 17 from its hole and seat, when the said member 15 is free to swing outward about the large dowel pin 16 as a center. The member 15 is further equipped with the slot-way 18 adapted 85 to receive the shank of the screw 19 which enters the threaded hole 20 in the gauge support 21, and the said gauge support 21 enters the channel guideway 22 in the member 15 with a neat sliding fit, thereby providing the horizontal adjustment of my gauge, which comprises the large flattened and flaring member 23, and the smaller associate swing member 24 adapted for attachment to the member 23 by means of the screw hole 25, the screw 26 and the threaded screw hole 27. It will now be readily appreciated how I may swing my gauge outward by lifting it, how I may secure horizontal adjustment by loosening and sliding the thumb screw 19 which moves the member 21, and how I may loosen the screw 26, and swing the gauge member 24 over the gauge member 23, and how I may control the position of a hat, for example shown at 28 in dotted lines. 75 The cutter 30 is shown securely clamped in the cutter carrier 31 by means of the set screw 32 which cutter carrier 31 is attached to the foot bar 33 of the sewing machine. The cutter carrier 31 is further provided with the small auxiliary gauge member 34 attached by means of the screw 35 and washer 36.

In operation, in cutting the brim of a felt hat for example, I adjust the gauge to control the desired depth of insertion into the machine and under the cutter of the felt brim, the brim is inserted, the gauge swung into closed and locking position, the foot-bar carrying the cutter is lowered, and the felt of the hat is pressed against the feed-dog of the sewing machine which imparts the motion to the felt of the hat against the cutter blade. I secure rapid and flexible adjustment, and a sharp clean cut of the fabric under the knife. In some operations there may be several thicknesses of material for example, and under certain conditions it is necessary or desirable to bring into play the small auxiliary gauge 34 to co-operate with the main gauge members 23 and 24. Whereas I have shown and described a swing adjustable gauge and co-operating cutter, with auxiliary gauge of a definite design, I may of course alter the shapes or forms of the gauge, cutter, and auxiliary gauge, without departing from the spirit of the invention or altering its mode of operation, or the mutually co-operating action of the gauge and cutter, or of the gauge, cutter and auxiliary gauge, and whereas I have shown my attachments upon a small sewing machine

for the hat industry, I may of course apply my devices to general and setting up sewing machines; or to any other kind of machine adapted to feed fabric under the cutter of its carrier.

Having described my invention, I claim:—

1. A work gauge for application to a sewing machine, comprising a bracket with a hinge member, a bar member adapted to swing on the hinge member, the said bar member carrying a gauge member horizontally adjustable, and a second gauge member pivoted on the first gauge member to provide a space therebetween for said work.
- 15 2. A gauge for application to a sewing machine, comprising a bracket with a hinge member, a bar member adapted to swing on the hinge member, a dowel pin rigid with the bar member and in association with the hinge member adapted to hold the bar member in a fixed position, a gauge member lat-

erally adjustable in the bar member, and a second gauge member pivoted on the first gauge member in spaced relation thereto.

3. A work gauge for application to a sewing machine, comprising a bracket member with a hinge member, a bar member adapted to swing on the hinge member, the said bar member provided with a channel-way and a slot-way, adapted to receive adjustably the shank portion of a gauge member, a thumb screw adapted to clamp the said shank portion immovably in the channel-way of the said bar member, a major gauge member carried by the said shank portion, and a minor gauge member adjustably secured thereto to provide a space therebetween for reception of the work.

Signed at New York city, in the county of New York and State of New York this 25th day of May, A. D. 1927.

ANNA MADELINE WENZEL.
